UNITED STATES PATENT OFFICE.

DANIEL W. CLARK, OF LOS ANGELES, CALIFORNIA.

CORE BOX FOR PISTONS.

Application filed December 3, 1921. Serial No. 519,760.

To all whom it may concern:

Be it known that I, DANIEL W. CLARK, a citizen of the United States, and a resident of Los Angeles, in the county of Los Angeles and State of California, have invented new and useful Improvements in Core Boxes for Pistons, of which the following is a specification.

This invention relates to core boxes partaking somewhat of the character, and for the purpose shown in patents granted to E. W. Clark Nos. 1,347,080; 1,347,081; and 1,378,524, dated respectively, July 20, 1920; July 20, 1920; and May 17, 1921.

In the manufacture of light weight pistons it has become essential, in order to provide a minimum thickness of metal in the wall and head of the piston, to thoroughly reinforce the skirt and head for resisting the shock and strain due to the operation of pistons in an internal combustion engine. In order to provide reinforcing ribs for this purpose, special core boxes have been provided, as shown in the above named patents, whereby plates are movably held in the core box so as to be withdrawn therefrom after the core has been made, and prior to the disassembling of the core box, for the purpose of stripping the ribs from the recesses in the core, so as to prevent damage being done to the core around said recesses.

In the present invention it is an object to provide in addition to the usual character of the ribs and core forming means disclosed in the said patents, additional ribs around the wrist pin bosses, so as not only to thoroughly brace said bosses but to better reinforce the walls of the piston in the vicinity of the bosses. One of the ribs of my improvement is arranged in a horizontal plane and is transversely disposed relative to the usual longitudinal ribs in the core box. In order to form these rib recesses in the core it is necessary, and it is therefore an object of my invention to provide means for stripping these additional ribs from the core and for forming corresponding recesses in the core thereby.

It is a further object of my invention to provide a modification and means for withdrawing the longitudinal ribs from the core box in planes paralleling the axis of the piston or core, and for withdrawing the relatively right angular ribs at the pin bosses from the core box. Means is also provided for adjusting the head forming member rela-

tive to the skirt forming members of the core box, so as to regulate the length of the skirt and the distance from the head to the center of the pin bosses.

Other minor objects may appear as the description progresses.

I have shown one practical embodiment of my invention in the annexed drawings, in which:

Fig. 1 is an inverted elevation of my core box; partially in section, in a plane cutting the center of one of the wrist pin bosses.

Fig. 2 is an inverted sectional elevation of the same, in a plane at right angles to Fig. 1.

Fig. 3 is a transverse sectional plan of the same in a plane cutting the wrist pin bosses.

Fig. 4 is a plan of the interior of the adjustable end member for the core box.

Fig. 5 is a perspective view of a piston showing the ribs formed therein by means of my improved core box; and

Fig. 6 is an elevation of a core made from a core box preparatory to the casting of a piston therefrom.

As shown in the drawings, the core comprises a body split in the center and formed of like members B, and B', with semi-cylindrical central portions 1, 1, forming a circular interior when positioned together for use, as shown in Fig. 1, and having a core print forming portion 3 at one end thereof, with a flaring recess 4 corresponding to the size and form of the core print. Intermediate the hollow portions 2 and 4 of the body I provide an annular rib 5 which extends slightly inwardly from the inner periphery of the portion 2 and provides a restricted opening 6 between the hollow portions 2 and 4. The core print forming members 3, 3, have matched lugs 7, 7, with apertures 8, 8, thereby, by means of which the two like halves of the body may be caused to register when dowels or pins are inserted through said apertures.

The body portions B and B' have like bosses 9, 9, formed thereon in diametrical alignment at right angles to the abutting faces of the body members, and said bosses extend outwardly from the outer periphery of the portions 1 of the body members for a substantial distance. Plugs P, P, are adapted for insertion in the bores 10, 10, of said bosses and have heads 11, 11, which abut the outer faces of the bosses. Central reduced portions 12, 12, which slidably engage the bores 10, 10, of said bosses are still further

reduced and tapered, and portions 13, 13, which extend inwardly into the recess 2 of the body and correspond in size and form to the wrist pin bosses of the pistons to be formed by the core box.

One end of the core box is open and is adapted to adjustably receive a head H which has an annular extension 14 adapted to fit into the open end of the box for a substantial distance for reducing the diameter and area of the recess 2 of the box at the head where the piston ring grooves are provided. This construction permits of a greater thickness of metal in the upper portion of the piston opposite the ring grooves and may be of a length corresponding to the number of grooves provided in a piston.

The head H has a central boss 15, in which the end 16 of a stem S is attached by threading or otherwise, and a web 17 connects the boss 15 with the annular portion 14 of said head. The web portion of said head H is externally threaded to receive an adjustment ring R and said ring has a plurality of pins or screws 18 held therein and arranged so that the heads of said screws will contact with the outer end of the core box body, when the head member H is adjusted inwardly to a desired extent.

Now, it will be understood that the adjustment of the ring R on the head will serve to regulate the distance the portion 14 of said head extends into the core box body, thus correspondingly regulating the ring groove portion of a piston.

The stem S slidably carries a movable end member E which is bored at 19 to receive said stem and has a knob 20 on the outer end thereof by means of which said member may be inserted in or withdrawn from operative connection with the head H and body members B and B'. When said end member is in operative position, the inner face of the annular wall 21 thereof will abut the outer face of the annular ring R.

A disc 22 is provided on the interior of the member E in abutment with the web 23 of said member, and is bored to receive and adapted to be fixed to the stem S. Said disc has a plurality of radially formed slots 24, 24, etc., in which the ends of a plurality of plates 25, 25, etc., are adapted to be inserted, and held by means of set screws 26, 26, carried in the annular portion 21 of end member E.

All of the ribs 25, with the exception of the two which intersect the wrist pin bosses 13, 13, are similar in size and form; and the outer ends thereof are of a width substantially corresponding to the length of the bosses 13, while the inner portions thereof are tapered so as to merge with the inner periphery of the core box at a point near the annular rib 5 thereof, as clearly shown in Fig. 2.

In the form of core box shown I have provided an annular rib 27 on the inner end of boss 15 of the head H and the ribs 25 are slightly curved in the plane of said rib so as to intersect said rib and to form in the core continuous recesses intersecting with the recess formed by the annular rib 27.

The outer edges 28 of the ribs 25 are straight and closely fit the inner periphery of the core box, and are adapted to slide thereover when the member E is moved outwardly on the stem S. The pair of ribs 25 which intersect the wrist pin bosses 13 have their widest portions extended substantially inwardly into contact with the periphery of the bosses 13, and the innermost portions 29 thereof are tapered and reduced in size, and are adapted to slidably seat in slots 30 which are formed longitudinally through the bosses 13.

Now, it will be observed that when a core is to be made by means of my improved core box, preparatory to the manufacture of a piston, the parts are positioned as shown in the drawings, and after the core is formed on the interior of the box the end member E may be moved slidably on the stem S for a distance sufficient to completely withdraw the ribs 25 from the core, thus serving to strip the ribs from the core and prevent damage thereto. To this end the head member H is radially slotted at 31 so as to permit the movement of the ribs 25 therethrough and the slots in the head of the ribs register with those in the end member E.

As hereinbefore stated, it is desirable to brace the wrist pin bosses 13 horizontally or transversely of the core box body, and for this reason I provide plates or ribs 32, 32, which are fixed centrally in the bosses 13, 13 and have their ends 33, 33, extended outwardly on opposite sides of said bosses and tapered so as to abut the adjacent ribs 25, 25 on opposite sides of said bosses. This is shown in Fig. 3.

The bosses 9, 9, on the body members B and B' are slotted transversely so as to slidably receive the ribs 32, 32, and to permit the withdrawal of said ribs from the body in horizontal and radial planes after the ribs 25 have been stripped from the core. It will be observed by reference to Fig. 1 that the portions 32 extend through the bosses 13 and have apertures therein so as to permit the extension of the rib portions 29 therethrough when the core box is set up and it is necessary that the ribs 29 be removed from the core box before the plugs P can be withdrawn.

In Fig. 6 I have shown a core of the character adapted to be formed in the core box herein shown and described. Said core comprises a body C of sand and oil, or other ingredients usually provided in foundry practice. The core print 34 is formed by

means of the portion 3 of the core box, and the adjacent groove 35 therein is formed by means of the annular rib 5. The longitudinal recesses 25' are formed by means of the longitudinal ribs 25. The transverse recesses 32' are formed by means of the transverse ribs 32, and the wrist pin boss recesses 13' are formed by means of the members 13. In the manufacture of pistons such as is shown in Fig. 5, the core is first formed and then a mating mold is formed by means of a pattern which is slightly larger than the core, the two halves of the mold being then placed together and metal poured in the space around the core. Thus, the reduced portion 14' of the core will provide a correspondingly thick wall 14" on the piston, and the completed piston will then embody a relatively thin cast metal skirt 36 with inwardly extended pin bosses 37, 37, on the interior thereof, and a plurality of longitudinal ribs 38, 38, merging with a central annular rib 39 on the head, and having their reduced tapered portions extended downwardly on the skirt. The pair of ribs intersecting the pin bosses will be continued below the pin bosses, as at 40, and such portions will correspond to the lower portions of the other ribs 38, while the transverse ribs 41 will be formed at right angles thereto.

Now, in operation, the members B and B' are first fitted together so as to form a complete cylindrical unit, the plugs P, P, are then inserted in the bosses 9, and the head H in the open end of the body, thereafter the end member E is moved inwardly on the stem S, so that the ribs 25 carried thereby will be properly positioned on the interior of the body B. The members B and B' being suitably clamped together, the sand and other ingredients of the core are then placed in the interior of the box and after a preliminary setting, the box is disassembled in order, the core is removed, and hardened and the casting operation of the piston follows.

While I have shown a practical form of core box for illustrating my present invention, I may modify and alter the same within the scope of the appended claims without departing from the spirit thereof.

What I claim is:

1. A core box comprising a body having diametrically opposite apertures in the wall thereof, plugs detachably held in said apertures, and plates held in the inner ends of said plugs and slidably movable therewith through said body, for the purpose described.

2. A core box comprising a body having diametrically opposite apertures in the wall thereof, plugs detachably held in said apertures, and plates held in the inner ends of said plugs and slidably movable therewith through said body, and a plurality of other

plates slidably held in said body and movable at right angles to said first mentioned plates, for the purpose described.

3. A core box comprising a body having diametrically opposite apertures in the wall thereof, plugs detachably held in said apertures, plates held in the inner ends of said plugs and slidably movable therewith through said body, and a plurality of other plates slidably held in said body and movable at right angles to and through said first mentioned plates, for the purpose described.

4. A core box for pistons comprising a body member having diametrically aligned and outwardly extending bosses formed on the wall thereof, provided with aligned bores therethrough, plugs slidably held in said bosses and having portions extending substantially inwardly into said body, and diametrically disposed plates carried in the inner portions of said plugs and also extending substantially into the interior of said body, for the purpose described.

5. A core box for pistons comprising a body member having diametrically aligned and outwardly extending bosses formed on the wall thereof, provided with aligned bores therethrough, plugs slidably held in said bosses and having portions extending substantially inwardly into said body, diametrically disposed plates carried in the inner portions of said plugs and also extending substantially into the interior of said body, and a plurality of other plates slidably held in said body and disposed at right angles to said first mentioned plates, for the purpose described.

6. A core box for pistons comprising a body member having diametrically aligned and outwardly extending bosses formed on the wall thereof, provided with aligned bores therethrough, plugs slidably held in said bosses and having portions extending substantially inwardly into said body, diametrically disposed plates carried in the inner portions of said plugs and also extending substantially into the interior of said body, and a plurality of other plates on the interior of said body disposed at right angles to and movable through said first mentioned plates, for the purpose described.

7. A core box for pistons comprising a sectional body, external bosses on said body having bores extending horizontally therethrough, plugs insertable in said bores having extensions projecting substantially into the interior of said body, and having diametrically disposed ribs extending outwardly therefrom for providing a corresponding recess on the core, said bosses being slotted to receive said ribs, and said plugs being removable from the core through said body.

8. A core box for pistons comprising a sectional body, external bosses on said body, having bores extending horizontally there-

through, plugs insertable in said bores having extensions projecting substantially into the interior of said body, and having diametrically disposed ribs extending outwardly 5 therefrom for providing a corresponding recess on the core, said bosses being slotted to receive said ribs, and said plugs being removable from the core through said body, and a plurality of other ribs disposed at 10 right angles to the ribs in said plugs, and having portions extending through said plugs for forming corresponding recesses in the core.

9. A core box for pistons comprising a 15 body having plugs laterally movable in the wall thereof, and a pair of relatively right angularly disposed plates extending through each of said plugs on the interior of said body for forming corresponding rib recesses 20 in the core.

10. A core box for pistons including separable body members diametrically alined, 25 plugs removably held therein, a head forming member closing one end of said body and adjustable relative thereto, an end member adjustable relative to said head member and having a plurality of plates carried thereby and slideable through said head member into the interior of said body for forming 30 corresponding rib recesses in the core, the inner ends of said plugs being extended substantially into the interior of said body, and certain of said plates being extended therethrough for continuing the rib recesses 35 on opposite sides of said plugs.

11. A core box for pistons including separable body members, diametrically alined plugs removably held therein, a head forming member closing one end of said body 40 and adjustable relative thereto, an end member adjustable relative to said head member and having a plurality of plates carried thereby and slideable through said head member into the interior of said body for forming 45 corresponding rib recesses in the core, the inner ends of said plugs being extended substantially into the interior of said body, certain of said plates being extended therethrough for continuing the rib recesses on 50 opposite sides of said plugs, and relatively right angularly disposed plates carried in said plugs for forming transverse rib recesses on the core, as described.

12. A core box for pistons comprising a

hollow body member, a head adjustable into 55 one end of said body, a ring on the outer end of said head for adjusting the thrust of said head into said body, and a plate holding member concentrically mounted on said head and having a plurality of plates slideable 60 through said head and into said body, for the purpose described.

13. A core box for pistons comprising a pair of like body members, having a cylindrical support, a core print forming member on one end thereof, a head forming member on the other end thereof, an end member adjacent to said head and held relative thereto, a plurality of plates carried in said end member and slideable through said head member and into the interior of said body for forming a corresponding rib recess longitudinally of the core, a pair of diametrically alined bosses on said body members, 70 plugs insertable in said bosses and having reduced extensions on the inner ends thereof projecting substantially into the interior of said body for forming wrist pin boss recesses in the core, a transverse rib recess forming member carried in the end of each of said 75 bosses, the longitudinal plates at said plugs being extended through said bosses, for the purpose described.

14. A core box for pistons including a pair of like semi-cylindrical body members, 80 capable of being held together in a core forming operation, a head forming member on one end of said box, a core print forming member on the other end thereof, a plurality of longitudinal plates commonly supported and slideable through said head member into the interior of said core box for forming longitudinal rib recesses on the core, a pair of diametrically alined bosses formed on the exterior of said core box, 85 removably held plugs in said bosses having wrist pin boss recesses forming portions on the inner ends thereof, plates carried in said bosses and disposed at right angles to said longitudinal plates for forming transverse 90 ribs on the peripheries of said core, adjacent said wrist pin boss recesses, said external bosses being slotted to slidably receive said plates.
